UNITED STATES PATENT OFFICE.

WILLIAM M. BARKER, OF CANTON, AND LOUIS C. BONNOT, OF LOUISVILLE, OHIO.

PULVERIZING MILL.

Application filed July 23, 1924. Serial No. 727,699.

The invention relates to a rotary drum grinding or pulverizing mill partly filled with balls, pebbles or the like, and the object of the improvement is to provide a machine which can be operated at slow speed and will continuously deliver a predetermined unvarying powdered product, without any adjustments or changes in the machine, and without the use of screens or other separating or grading apparatus.

The improved mill is well adapted for pulverizing small lump or slack coal for supplying powdered fuel directly in a furnace or a fuel feeding system, and the invention is illustrated and described with reference to such a use of the mill, without intending to limit it thereto.

In mills of this type, an axial tube extending into and sometimes through the mill has been used for withdrawing the powdered product from the drum by suction through one end of the tube; and in the rotation of the drum, the grinding balls have been carried by frictional engagement with each other and with the peripheral wall of the drum supplemented by the action of centrifugal force, upward on the rear side of the axial tube and thence forward over and above the same, so as to fall freely through space downward, either against the peripheral wall of the drum or upon the grinding balls in front of the tube.

Such a movement of the balls is ineffective for grinding purposes in substantially all of the forward and downward portion of their orbits, and is also objectionable for the reason that the impinging action upon the forward peripheral wall of the drum, wears the same without accomplishing any grinding action upon the material to be powdered.

The present invention involves the use of a stationary deflecting wall extending directly upward from the rear side of the axial tube to the peripheral wall of the drum, and filling the entire distance between the end walls thereof, which serves as a baffle or abutment for the grinding balls and ground materials moving upward in the rear side of the drum, to deflect the same when falling forward so as to shower downward upon the ascending body of balls and raw material in rear of the axial tube, for a direct grinding action therewith.

When a fixed axial suction tube is used for

withdrawing pulverized material from a grinding drum, it has heretofore been thought necessary or desirable to extend a tube upward therefrom to form a dust receiving opening in the upper part of the drum. It has been found, however, that the best results are obtained by providing a dust receiving opening in the upward forward side of the axial tube itself, preferably midway between the ends of the drum, and to cause the greater portion of the powdered material to enter the same by passing downward from the rear side and thence forward under and upward in front of the axial tube.

It is also preferred to further define the dust removing opening in the axial tube by providing upright walls at each end and at the back thereof, and to secure thereon a roof plate inclined downward and forward from the deflecting wall a substantial distance to overhang the mouth in the forward side of the exhaust box thus formed so as to shed forward any ground material which finds its way into the upper portion of the drum, and prevent anything but finely powdered material from finding its way into the mouth of the exhaust box.

A further feature of the present improvement relates to the admission of air into the drum through an annular opening in each end thereof around the axial tube; so as to carry powdered material into the mouth of the exhaust box from both ends of the drum, and also from both sides of as well as from below the axial tube.

These annular openings are preferably formed large enough so as to render the interior of the drum visible from each end thereof, and enable an attendant to properly regulate the supply of material to be ground. The same annular openings also permit the material to overflow from one or both ends of the drum, whenever it is overfed, thereby rendering it impossible to choke the drum by overfeeding the same.

A final feature of the present improvement involves the location of a feed chute downward and inward through the axial tube at one end annular opening of the drum, so as to deliver the raw material to the middle of the drum immediately below the axial tube, where it is at once subjected to the intensive grinding action of the shower of balls falling at the rear thereof.

Apparatus embodying the present inven-

110

tion is illustrated in the accompanying drawings, forming part hereof, in which—

Figure 1 is a side elevation of the pulverizing mill showing the grinding drum, the feed chute and the discharge tube in axial section;

Fig. 2, an end elevation of the drum, looking from cross section line 2—2, Fig. 1;

Fig. 3, a cross section elevation of the mill, 10 on line 3—3, Fig. 1;

Fig. 4, a cross section elevation of the mill on line 4—4, Fig. 1;

Fig. 5, a detached perspective view of the exhaust box forming the exhaust mouth; 15 and

Fig. 6, a detached perspective view of the roof plate thereof.

Similar numerals refer to similar parts throughout the drawings.

20 The grinding drum 6 may be provided on each end with a peripheral track band 7 riding upon flanged wheels 7' mounted on shafts 8, and the drum may be rotated by a central annular girt gear 9 meshing with a 25 pinion 10 mounted on one of the shafts 8, which may be driven from any suitable source of power.

An axial tube comprising end sections 11 and 11^a and an intervening exhaust box 11^b 30 extends through enlarged central openings in the ends of the drum, and may be supported on standards 12 at each end thereof. One end 11 of this tube may communicate directly with the inlet orifice of an exhaust fan 13 operated by an electric motor 14 and having its discharge pipe 15 communicating with the combustion chamber of a furnace or other place for delivering powdered material; and the other end 11^a of the tube preferably carries a downward and inwardly inclined chute 16, for feeding coal slack or other raw material to be ground from a supply tube 17 through one end opening of the drum to the middle thereof below the axial tube.

40 The middle portion 11^b of the axial tube may be in the form of a box with upright walls 18 and 18' on each end, one of which forms a partition transversely shutting off 45 one end 11^a of the tube, and the other one being provided with an opening 18^b communicating with the exhaust end section 11 of the tube; and with an upright back wall 19 which closes the opening between the rear edges of the walls 18 and 18'.

A roof plate 20 is secured across the top of the end walls, and the forward wall of the box 11^b terminates in a lip 21 directly in front of the axis of the tube, so as to form a dust 50 receiving mouth 22 between the end walls of the box immediately above the plane of the axis of the tube, and under the overhanging forward end of the roof plate.

55 The roof plate 20 extends endwise each way close to the end walls of the drum so as to

overhang the end walls of the exhaust box; and to the rear of the back wall 19 is secured a stationary deflecting wall 23 extending upward close to the peripheral wall of the drum, and also extending each way close to the end walls of the drum, so as to form sheltered spaces 24 above the axial tube, between the end walls of the box and end walls of the drum.

60 The central openings in the end walls of the drum are preferably defined by outwardly flared collars 25, of such diameter as to form annular openings 26 around the axial tube for the admission of air at each end of the drum. The diameter of one opening is preferably larger than that of the other, so that overfed material will ordinarily escape from one end only of the drum.

65 The described apparatus having a drum some four and one-half feet in diameter and two feet long, and an axial tube about twelve inches in diameter, may be used with good results for producing powdered fuel from slack coal, by rotating the drum at the rate of some twenty-eight or twenty-nine 70 R. P. M., in conjunction with a centrifugal fan producing a suction pressure of some three and one-half inches of water.

75 When the drum is stopped after a rotation in the direction of the arrow, the grinding balls assume a position somewhat as shown in Fig. 2, but when the drum is rotated in the direction of the arrow for a grinding operation, the balls move somewhat in the manner shown in Fig. 3; and when a supply of slack coal or the like is fed into the rotating drum through the chute 16, the same is received and acted upon immediately and directly, somewhat as shown in Figure 4. The air currents produced by the suction pressure of the centrifugal fan, take the course as shown by the broken line arrows in Figs. 1 and 4, which winnows out the fine powder which has been produced by the grinding operation, and carries the same into the receiving mouth of the exhaust box.

80 By these means, the grinding balls and the coarser particles of the raw material are kept constantly at work with each other, in the lower and rear part of the drum, without any of the balls moving into the upper and left part thereof; and without any of the ground material passing by rotating or centrifugal force into the upper or left part of the drum, excepting only the very small portion of the finer particles which may find their way between the upper and end edges of the deflecting plate and the peripheral and end walls of the drum.

85 Aside from this small portion of the ground material, which is again deflected forward by the roof plate overhanging the discharge mouth of the exhaust tube, the only material which can find its way to the mouth

of the exhaust box is the finely pulverized material which is winnowed from the mass of grinding balls and the coarser particles of the raw material, in the lower portion of the drum; whence the fine powder is carried through the annular zone immediately surrounding the axial tube 11, which by reason of the action of the centrifugal force upon the larger particles, is substantially free of all material, excepting only the floating powder and excepting only the slender stream of raw material flowing into the middle of the drum.

Thus the air currents which are drawn inward through the annular openings in the ends of the drum are free to act selectively upon the pulverized powder, more particularly in the lower and forward parts of the drum, and to carry the same into the centrally located mouth of the exhaust box, while all the coarser particles in the bottom, lower and rear portions of the drum are being ground by abrading contact with each other and with and between the grinding balls. At the same time the coarser particles of the small portion of the ground material which finds its way around the edges of the deflecting plate into the forward side of the drum, are carried by rotary and centrifugal force, and by the action of gravity, downward in front of the exhaust mouth, and are deflected by the roof plate so far forward that they are not drawn into the same, but drop on downward into the mass of grinding balls and raw material in the bottom of the drum.

The deflecting wall 23 may be and preferably is provided with a thick layer or facing of resilient material 23' on its rear side, for receiving the impinging action of the grinding balls and raw material; and the same serves not only to accelerate the rebound and increase the activity of the grinding balls, but to deaden or soften the sound of the machine when in operation.

When properly fed with raw material, the machine reduces the same to a fine powder and continuously delivers a powdered product of uniform predetermined fineness, depending upon the movement of air as controlled by the suction pressure, which may be varied by a damper 27 in the exhaust tube or by the speed of the exhaust fan.

Although the mill is intended for grinding dry materials, it can be successfully operated for pulverizing substances carrying a considerable amount of moisture without materially affecting its grinding capacity; and if desired, a heating and drying medium may be drawn into the mill, either through the feed chute 16 or through the end section 11^a of the axial tube, which for that purpose may be provided with openings 28 within the drum, and to control the amount of air which may be thus received,

a damper 29 is preferably provided in this section of the tube.

We claim:

1. A mill for pulverizing raw material, including a rotary drum with grinding media therein, an axial exhaust tube having an upwardly opening receiving mouth within the drum, and stationary means above the receiving mouth and extending substantially contiguous to the inner wall of the drum for deflecting all the grinding media and ground material downward in the rear of the axial tube. 75

2. A mill for pulverizing raw material, including a rotary drum with grinding balls 80 or the like therein, an axial exhaust tube having an upwardly opening receiving mouth within the drum, and stationary means above the receiving mouth and extending substantially contiguous to the inner wall of the drum for deflecting all the grinding balls and ground material downward in the rear of the axial tube. 85

3. A mill for pulverizing raw material, including a rotary drum with grinding balls 90 or the like within, an axial exhaust tube having an upwardly opening receiving mouth within the drum, and a stationary angled partition wall in the rear of the receiving mouth extending upward from the tube substantially contiguous to the inner wall of the drum and endwise to the end walls thereof, for deflecting all of the grinding balls and ground material downward in rear of the axial tube. 95 100

4. A mill for pulverizing raw material, including a rotary drum with grinding balls or the like therein, an axial exhaust tube having a receiving mouth within the drum, and a stationary partition wall faced with 105 resilient material in the rear of the receiving mouth and extending upward from the tube to the peripheral wall of the drum and endwise to the end walls thereof for deflecting all of the grinding balls and ground material downward in rear of the axial tube. 110

5. A pulverizing mill including a rotary drum with grinding balls or the like therein, an axial exhaust tube having a receiving mouth within the drum, there being an annular opening in each end wall of the drum. 115

6. A pulverizing mill including a rotary drum with grinding balls or the like therein, an axial exhaust tube having a receiving mouth within the drum, there being an annular opening in each end wall of the drum around the axial tube. 120

7. A pulverizing mill including a rotary drum with grinding balls or the like therein, an axial tube having a central receiving mouth opening directly in its upper wall, upright walls at each end and in rear of the mouth and a downward, forward inclined roof plate thereon, forwardly overhanging the exhaust receiving mouth. 125 130

8. A pulverizing mill including a rotary drum with grinding balls or the like therein, an axial exhaust tube with a receiving mouth opening directly in its upper wall and shielding means for the receiving mouth opening only in front thereof with a roof plate forwardly overhanging the receiving mouth. 20
9. A pulverizing mill including a rotary drum with grinding balls or the like therein, an axial exhaust tube with a receiving mouth opening directly in its upper wall, and shielding means for the receiving mouth opening only in front thereof. 10
10. A pulverizing mill including a rotary drum with grinding balls or the like therein, an axial exhaust tube having an exhaust receiving mouth opening directly in its upper wall, a chute extending through one end 25 and a way for feeding raw material into the middle of the drum below the axial tube. 15
11. A pulverizing mill including a rotary drum with grinding balls or the like therein, an axial tube having an exhaust receiving mouth opening directly in its upper wall, and a way for feeding raw material into the middle of the drum below the axial tube. 20
12. A pulverizing mill including a rotary drum with grinding balls or the like therein, an axial tube having an exhaust receiving mouth opening directly in its upper wall, and a way for directing a heating medium into the drum. 25

In testimony that we claim the above, we have hereunto subscribed our names.

WILLIAM M. BARKER.
LOUIS C. BONNOT.
